US00D813122S

(12) **United States Design Patent** (10) **Patent No.:** **US D813,122 S**
Johnson et al. (45) **Date of Patent:** **** Mar. 20, 2018**

(54) **ERGONOMIC PEDAL**

(71) Applicants: **Paul R. Johnson**, Brentwood, TN (US);
Robert E. Johnson, Hendersonville, TN (US)

(72) Inventors: **Paul R. Johnson**, Brentwood, TN (US);
Robert E. Johnson, Hendersonville, TN (US)

(73) Assignee: **Johnson Technologies Corporation**,
Nashville, TN (US)

(**) Term: **14 Years**

(21) Appl. No.: **29/474,669**

(22) Filed: **Dec. 22, 2014**

(51) LOC (11) Cl. **12-16**

(52) U.S. Cl.
USPC **D12/174**

Double Bass Drum Pedal, image post date Mar. 25, 2013, site visited Sep. 6, 2016, (online), <http://web.archive.org/web/20130325002745/http://www.off-set.net/Off-Set/Double_Bass_Drum_Pedal.html>.*

Primary Examiner — Kevin Rudzinski

Assistant Examiner — Sean D Lough

(74) Attorney, Agent, or Firm — Carrithers Law Office, PLLC

(57) **CLAIM**

The ornamental design for an ergonomic pedal, as shown and described.

DESCRIPTION

FIG. 1 is a perspective view of an ergonomic pedal showing my new design;

FIG. 2 is a front plan view thereof;

FIG. 3 is a back plan view thereof;

FIG. 4 is a right side view thereof;

FIG. 5 is a left side view thereof;

FIG. 6 is a top plan view thereof; and,

FIG. 7 is a bottom plan view thereof.

The broken lines shown in all of the figures illustrate portions of the ergonomic pedal that form no part of the claimed design. The broken lines showing the textured top surface of the ergonomic pedal represents environment and does not form a part of the claimed design.

1 Claim, 2 Drawing Sheets
